W. A. SLUSHER

ROLLER SKATE

Filed March 19, 1927

INVENTOR.
Walter A. Slusher

BY

Warren L. House
His ATTORNEY.

witness:

R. Hamilton

UNITED STATES PATENT OFFICE.

WALTER A. SLUSHER, OF KANSAS CITY, MISSOURI.

ROLLER SKATE.

Application filed March 19, 1927. Serial No. 176,701.

My invention relates to improvements in roller skates.

One of the objects of my invention is to provide a novel automatic braking mechanism for a roller skate, which is simple, cheap, durable, strong, not liable to get out of order, which is easily operable, which is so arranged and disposed as to not be liable to catch the clothing or cause the operator to be tripped, and which is efficient in operation.

My invention provides further novel adjustable means for attachment of the brake operating means to the leg of the operator.

The novel features of my invention are hereinafter fully described and claimed.

In the accompanying drawing, which illustrates the preferred embodiment of my invention,

Fig. 1 is a side elevation of a roller skate provided with my improvement.

Fig. 2 is a rear elevation of the same.

Fig. 3 is a plan view of the same.

Fig. 4 is a bottom view, partly broken away, of the same.

Fig. 5 is an enlarged section on the line 5—5 of Fig. 3.

Similar reference characters designate similar parts in the different views.

1 designates a foot rest of usual type, which is supported upon the usual front and rear carrying wheels 2 and 3, the rear end of the foot rest having attached to it straps 4 and 5 adapted to embrace the foot, the strap 4 having a buckle 6 adapted to be engaged by a strap 5.

Pivoted to the under side of the foot rest 1 on a transverse pin 7, mounted in the foot rest, is a braking device, which may comprise a brake shoe 8, which is disposed in front of the carrying wheel 3, and which is adapted to be forced to the braking position, shown in dotted lines in Fig. 5, in which position it will have braking engagement with the tread of the rear wheel 3.

45 A U-shaped operating member, which may comprise, in its transverse portion, two horizontal transverse aligned portions 9 of two rods, said portions 9 being mounted in and rigidly fastened to a sleeve 10. Said rods are each provided with an upwardly extending portion 11, said portions 11 constituting the arms of the U-shaped operating member. The portions 9 are oscillatably mounted in the foot rest 1.

55 The arms 11 of the U-shaped member are provided with means for releasable attach-

ment to the leg of the skater. Such attaching means may comprise two plates 12 and 13, which are respectively pivoted by horizontal transverse screws 14 and 15 to the upper ends 60 of the arms 11. Respectively fastened to the plates 12 and 13 are two straps 16 and 17, which are adapted to embrace the leg a short distance above the ankle joint. One end of the strap 16 is provided with a buckle 18 adapted for adjustable engagement with the strap 17, the opposite end of the latter being provided with a buckle 19, which is adapted for adjustable engagement with the adjacent end of the strap 16, as shown in Fig. 3. 70

By having the two straps 16 and 17 provided with the buckles 18 and 19 disposed respectively at opposite sides of the arms 11, the leg attachment means is adapted for releasable engagement with ankles of different 75 diameters, while retaining the arms 11 in a substantially upright position, as shown in Fig. 1.

The transverse portions 9—10 of the U-shaped operating member are, preferably, 80 disposed in a vertical plane forward of the vertical plane of the axis of the wheel 3.

Means are provided by which when the arms 11 of the operating member are swung rearwardly to the position shown in dotted lines in Fig. 5, the brake shoe 8 will be forced to the braking position against the tread of the wheel 3, as shown in dotted lines in Fig. 3, such means may comprise, as shown, a rearwardly extending arm 20, which may be an 90 integral portion of the sleeve 10, and which is disposed above the shoe 8, and normally in contact therewith.

For normally holding the brake shoe 8 out of contact with the wheel 3, a coil spring 21 95 encircles the pin 7, and has one end bearing against the under side of the shoe 8 and its other end bearing against the under side of the foot rest 1.

The arms 11 of the operating member are 100 so disposed with reference to the foot rest 1 as to be substantially in the vertical plane of the central portion of the ankle joint.

The forward portion of the foot rest 1 may be provided with the usual sole clamping members 22 which are adjustable toward and from each other by the usual transverse screw 23, opposite ends of which are respectively oppositely threaded.

The skate having been fastened to the shoe 110 and leg of the skater, when it is desired to apply the brake shoe 8 to the wheel 3, the

skater thrusts forwardly the foot, which is to apply the brake, and holds his foot in a position such that both wheels 2 and 3 will be in contact with the supporting surface upon which they are traveling. This will cause a bending at the ankle joint, which will swing the arms 11 of the operating member rearwardly to the position shown in dotted lines in Fig. 5, thereby swinging the sleeve 10 and arm 20, so that the latter will move downwardly and will force the brake shoe 8 into braking engagement with the wheel 3, as shown in dotted lines in Fig. 5.

By having the arms 11 of the operating member substantially in the vertical transverse plane of the ankle joint, it is not required to have any longitudinal slidable movement of the arms with respect to the foot rest 1, and an easy operating movement is effected for applying the brake. By disposing the brake shoe 8 so as to engage the tread of the wheel 3 at a place forward of the vertical plane of the axis of the wheel, wear of the wheel by engagement with the brake shoe is less and a better braking action is effected than would be the case if the brake shoe contacted with the wheel at the rear of the vertical plane of the axis.

I do not limit my invention to the structure shown and described, as many modifications, within the scope of the appended claims, may be made without departing from the spirit of my invention.

What I claim is:

1. In a roller skate, a foot rest, a rotary carrying wheel under and supporting said foot rest, a braking device pivoted to said foot rest so as to swing into and out of braking engagement with the tread of said wheel, an operating member having means for attachment to the leg, and means engaged by said member adapted to engage and force said braking device to the braking position.
2. In a roller skate, a foot rest, a rotary carrying wheel under and supporting said foot rest, a braking device pivoted to said foot rest so as to swing into and out of braking engagement with the tread of said wheel, an operating member having means for attachment to the leg and pivoted on a transverse axis to said foot rest, and means engaged by said member adapted to engage

and force said braking device to the braking position.

3. In a roller skate, a foot rest, a rotary carrying wheel under and supporting said foot rest, a braking device pivoted to said foot rest so as to swing to and from braking engagement with the tread of said wheel, an operating member having means for attachment to the leg and pivoted on a transverse axis to said foot rest, and a member fastened to and movable with said operating member and adapted to engage said shoe to force the latter to the braking position, when said operating member is swung rearwardly.

4. In a roller skate, a foot rest, a rotary carrying wheel supporting said foot rest, a braking device movable on said foot rest into and out of braking engagement with said wheel, a U-shaped operating member having its transverse portion pivotally mounted on said foot rest and having its arms provided with means for attachment to the leg, and means fastened to said transverse portion of said operating member adapted to engage and force said braking device to the braking position, when said operating member is swung in one direction.

5. In a roller skate, a foot rest, a rotary carrying wheel supporting said foot rest, a braking device movable on said foot rest into and out of braking engagement with said wheel, an operating member pivoted to said foot rest on a transverse axis forward of the vertical plane of the axis of said carrying wheel, and means actuated by said operating members, when the latter is swung in one direction, for forcing said braking device to the braking position.

6. In a roller skate, a foot rest, a rotary carrying wheel supporting said foot rest, a braking device movable to and from braking engagement with said wheel, a U-shaped operating member having its transverse portion pivoted to said foot rest on a transverse axis forward of the vertical plane of the axis of said wheel, and means actuated by said operating member for forcing said braking device to the braking position, when the operating member is swung in one direction.

In testimony whereof I have signed my name to this specification.

WALTER A. SLUSHER.
